F. J. STEINHAUSER.

Car-Track Clearer.

No. } 487. }
  } 31,491. }

Patented Feb. 19, 1861.

UNITED STATES PATENT OFFICE.

FRANK J. STEINHAUSER, OF LANCASTER, PENNSYLVANIA.

SNOW-PLOW.

Specification of Letters Patent No. 31,491, dated February 19, 1861.

To all whom it may concern:

Be it known that I, FRANK J. STEINHAUSER, of Lancaster city, State of Pennsylvania, have invented a new and useful

5 Improvement for Cutting and Shoveling Snow and Cutting Ice to Clear Railway-Tracks; and I do hereby declare that the following is a full and exact description thereof, reference being had to the accompanying drawings, and to the letters of reference marked thereon, making a part of this specification.

10 The nature of my invention consists in hoop-shaped cutters or snow breakers in front of machine attached to shafts containing a number of shovels set spirally on each side of machine, and ice breakers or toothed wheels fastened at the back end of machine to break the ice off the rails.

15 20 A represents the circular cutters or snow-breakers, which are located in front, for the purpose of breaking the snow in pieces, or removing any obstructions from the rails, so that the shovels B are relieved, and allowed 25 to work easier without injury. These cutters are shaped like a hoop, and are fastened to the end of shaft C.

B represents 24 shovels (more or less in number) on each side of frame D and are 30 attached to arms on the horizontal shaft C. These shovels are set in spiral form, so as to work with their faces outward and curved in the form of a flange of a horizontal revolving right and left screw, to throw the 35 snow out from the rails, several feet distance.

D represents the frame of an ordinary cow catcher or snow shovel commonly used on locomotives as a snow plow.

35 40 E are bevel wheels at back end of shaft C to operate the shaft, but I do not confine myself to the use of these bevel wheels, but

desire to use any mode of gearing that may be best attached to a locomotive, for driving the shafts C and shovels B.

F are the ice cutters or breakers located at the hind end of frame D and are composed of three heavy wheels on each side, so as to bear upon the rail. The center wheel G runs on the rail while the outside wheels F act as flanges on each side of rail. 45 The breakers G have teeth crosswise, like a cogwheel, to break the ice, while the wheels F have sharp cutter edges or flanges to cut the ice on each side of the rail. These ice breakers or cutters are attached to the back 50 end of frame to be used movably up or down, and are intended to be adjustable according to the impediments or obstructions that may be in the way, at crossings switches &c.

H are cross bars of wrought iron to brace and support the shafts C.

The advantages are, first, this machine can be applied to a passenger car engine, and effectually clear the track, by which time is 65 saved in traveling; second, it will perform the work that requires the employment of a large number of men and the economy in the saving of labor makes it of the highest utility.

70 What I claim as my invention, and desire to secure by Letters Patent is—

The circular breakers A and shovels B, together with the ice breakers F and G as arranged in combination with the ordinary 75 snow plow D for the purpose of removing snow and ice from railway tracks.

FRANK J. STEINHAUSER.
